UNITED STATES PATENT OFFICE

126,719

DESIGN FOR A TEXTILE FABRIC

John L. Koehne, New York, N. Y.

Application March 14, 1941, Serial No. 99,584

Term of patent 7 years

To all whom it may concern:

Be it known that I, John L. Koehne, a citizen of the United States of America, residing in New York city, county of New York, and State of New York, have invented a new, original, and ornamental Design for a Textile Fabric, of which the following is a specification, reference being had to the accompanying drawings, forming part thereof wherein,

I claim:

The ornamental design for a textile fabric, substantially as shown.

JOHN L. KOEHNE.
